CLAIM

The ornamental design for a false bottom tube with cap and plug, as shown and described.

DESCRIPTION

FIG. 1 is a front view of the false bottom tube with cap and plug illustrating the present design, with the back view being identical;

FIG. 2 is a top view of the false bottom tube with cap and plug as shown in FIG. 1;

FIG. 3 is a bottom view of the false bottom tube with cap and plug as shown in FIG. 1;

FIG. 4 is a left side view of the false bottom tube with cap and plug as shown in FIG. 1;

FIG. 5 is a cross-sectional view through line 5-5 of the false bottom tube with cap and plug as shown in FIG. 4;

FIG. 6 is a right side view of the false bottom tube with cap and plug illustrating the present design as shown in FIG. 1;

FIG. 7 is a cross-sectional view through line 7-7 of the false bottom tube with cap and plug as shown in FIG. 6;

FIG. 8 is a perspective view of the false bottom tube with cap and plug illustrating the present design as shown in FIG. 1;

FIG. 9 is a perspective exploded view of the false bottom tube with cap and plug and swab illustrating the present design as shown in FIG. 1; and,

FIG. 10 is a perspective exploded view of the false bottom tube with cap and plug shown in FIG. 1, with the swab removed.
